UNITED STATES PATENT OFFICE.

MADELON MOONEY, OF LOS ANGELES, CALIFORNIA.

DESIGN FOR A DOLL.

60,697.

Specification for Design.

Patented Mar. 21, 1922.

Application filed October 19, 1921. Serial No. 508,868. Term of patent 3½ years.

To all whom it may concern:

Be it known that I, MADELON MOONEY, a citizen of the United States, residing at Los Angeles, in the county of Los Angeles and State of California, have invented a new, original, and ornamental Design for a Doll, of which the following is a specification, reference being had to the accompanying drawing, forming a part thereof.

I claim:

The ornamental design for a doll, as shown.

Signed at Los Angeles, in the county of Los Angeles, and State of California, this 10th day of October, 1921.

MADELON MOONEY.

Witness:

JAMES R. TOWNSEND.
